UNITED STATES PATENT OFFICE.

LEVI K. SMEDES, OF NEW YORK, N. Y., ASSIGNOR TO H. E. TAYLOR & CO., OF SAME PLACE.

DESIGN FOR A CASKET.

SPECIFICATION forming part of Design No. 22,995, dated January 2, 1894.

Application filed November 16, 1893. Serial No. 491,157. Term of patent 3½ years.

To all whom it may concern:

Be it known that I, LEVI K. SMEDES, a citizen of the United States, residing at New York, in the county and State of New York, have invented and produced a new and original Design for Caskets, of which the following is a specification.

This design has for its object to provide a novel and ornamental casket which presents a characteristic and distinguishing appearance; and the leading feature of the design resides in an octagonal casket without butts at the angles, and having at the bottom vertical fluting, and at the top an ogee or cove with butts at the angles, with an ornamented band-like portion centrally around the body between the vertical fluting and the ogee or cove.

The design is illustrated by the accompanying drawing, which is a perspective view of the casket.

The body of the casket is made in the form of an endless octagon; that is, an octagon not broken by butts at the angles or corners B.

The octagonal casket is provided at the bottom with the vertical fluting C, and at the top with the ogee or cove D having butts E at the angles; while between the vertical fluting and the ogee or cove, the casket is provided with an ornamented band-like portion A, extending centrally around its body. The bottom portion of the casket is provided with rods F having ends G enlarged and turned inward or toward the casket, and along the rods are ornamental knobs H.

The design provides a very ornamental casket which presents a peculiar and characteristic appearance.

What I claim is—

The design for a casket, substantially as shown and described.

In testimony whereof I have hereunto set my hand in the presence of two subscribing witnesses.

L. K. SMEDES.
